UNITED STATES PATENT OFFICE

MONROE HARRISON, OF CHICAGO, ILLINOIS

DESIGN FOR A DRINK-DISPENSING APPARATUS

Application filed September 18, 1930. Serial No. 37,012. Term of patent 7 years.

To all whom it may concern:

Be it known that I, MONROE HARRISON, a citizen of the United States, residing at Chicago, in the county of Cook and State of Illinois, have invented a new, original, and ornamental Design for Drink-Dispensing Apparatus, of which the following is a specification, reference being had to the accompanying drawings, forming a part thereof.

In the drawings—

The figure is a perspective front elevation

of a design for drink dispensing apparatus embodying my invention. The drawing shows the apparatus as viewed from the dispensing side, where the spigots and a drip pan are shown, the opposite side not having these features.

What I claim is:

The ornamental design for drink dispensing apparatus, as shown and described.

MONROE HARRISON.
